US0D1081430S

(12) **United States Design Patent** (10) Patent No.: **US D1,081,430 S**
(45) Date of Patent: ** Jul. 1, 2025

(54) **SMOKE AND CARBON MONOXIDE
DETECTOR**

(71) Applicant: **Yunlong Zhong**, Shenzhen (CN)

(72) Inventor: **Yunlong Zhong**, Shenzhen (CN)

(**) Term: **15 Years**

(21) Appl. No.: **29/941,370**

(22) Filed: **May 9, 2024**

(51) LOC (15) Cl. **10-05**

(52) U.S. Cl.

USPC **D10/106.5**

(57) **CLAIM**

The ornamental design for a smoke and carbon monoxide detector, as shown and described.

DESCRIPTION

FIG. 1 is a front perspective view of a smoke and carbon monoxide detector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the smoke and carbon monoxide detector, which form no part of the claimed design.
